PULVERIZATION

Martin Frisch, New York, N. Y., assignor to Foster Wheeler Corporation, New York, N. Y., a corporation of New York

Application May 26, 1938, Serial No. 210,091

10 Claims. (Cl. 83—9)

This invention relates to the comminution of materials and more particularly pertains to the pulverization of fuels such as coal and the like.

This application is a continuation-in-part of application Serial No. 53,362, filed December 7, 1935.

Large scale pulverization of fuels, such as coal, for firing the furnaces of steam generators and other uses, is generally accomplished in pulverizing mills into which is separately fed the material to be pulverized and a stream of air. The pulverized material is entrained in the air stream flowing through the mill and the mixture is withdrawn from the mill at one point thereof and is conducted either to storage or to burners. In some instances the material to be pulverized is fed into the mill at one point thereof and the air is supplied at an adjacent point, while in other cases the air is supplied at an entirely different or at a substantially oppositely disposed point of the mill with respect to the point at which the material is fed. In these latter instances, particularly with pulverizing mills of the ball type, it has been found that with a given ball charge and power input, the fuel is pulverized much finer than is required for satisfactorily utilizing the fuel in burners or the like. With ball mills of the rotating drum type the trunnion diameters are definitely limited for any given size mill so that it is difficult to take advantage of the increased grinding capacity, due to the fact that when the air flowing through the mill is materially increased over normal practice, the pressure drop through the mill becomes uneconomically high in addition to which there is a tendency for the mill operation to become unstable.

Moreover, with present practice, preheated air is supplied to the mill under pressure which is usually throttled by dampers prior to the introduction of the air to the mill since it is desirable to have the mill operating under suction rather than under pressure. The throttling of this available air pressure ordinarily results in an economic loss.

The present invention overcomes the foregoing disadvantages and provides pulverizing apparatus, and a method of pulverizing materials, which reduces the fuel or other material to a degree of fineness which can be satisfactorily utilized with a large output of the pulverized material. Additionally, with the present invention the available air pressure instead of being throttled with dampers is converted into a relatively high velocity prior to its introduction into the mill thus advantageously utilizing the air pressure so that

the required quantity of air may be admitted to the pulverizer through smaller areas than are now required and without putting the mill under superatmospheric pressure.

Other purposes and advantages will become apparent from the following description considered in connection with the accompanying drawings forming a part thereof in which:

Fig. 1 is a view in elevation of a preferred form of pulverizing apparatus embodying the present invention;

Fig. 2 is a vertical sectional view on an enlarged scale, taken on line 2—2 of Fig. 1;

Fig. 3 is a vertical longitudinal sectional view, on an enlarged scale, of the pulverizer shown in Fig. 1; and

Fig. 4 is a combined sectional and elevational view of another form of ball mill embodying the invention.

Like characters of reference refer to the same or similar parts throughout the several views.

The invention is disclosed as embodied in and carried out by a pulverizing mill of the rotating drum, ball type but it will be understood that this form, although preferred, is merely illustrative of one application of the principles of the invention and that the invention may be applied to other types of mills, such as stationary drum types, having grinding means other than a ball charge.

Referring to Figs. 1 to 3 of the drawings, reference character 10 designates the drum of a pulverizing mill, the drum in this instance being generally frusto-conical in form and being provided at its ends with trunnions 11 and 12, which are mounted in and rotatably supported by bearings 13 and 14 respectively, resting on supporting members 15 and 16 respectively. Mounted exteriorly at one end of the drum 10 is the gear 17 by means of which the drum is rotated on its trunnions by any suitable driving means, not shown. The drum is lined with a suitable form of liner 18 and is provided with a charge of grinding balls 19.

In the form of the invention shown, the material to be pulverized is fed to the drum simultaneously at both ends thereof and air, preferably heated, is also supplied to the drum simultaneously at both ends thereof. Moreover, the pulverized material and air mixture is withdrawn from the drum simultaneously at both ends thereof and classifiers are supplied at both ends of the drum so that the oversize material carried from the drum by the air stream will be separated from the material which has been suffi-

ciently pulverized and the oversize is returned to the drum at both ends thereof simultaneously.

The material to be pulverized is fed from a source of supply to a feeder 20 driven by an electric motor 21 or other suitable means and the feeder delivers the material at the desired rate to vertically inclined feed pipes 22 and 23 which are connected together at their upper ends and at their lower ends are connected to combined feeders and classifiers 24 and 25 respectively. The material is delivered by the feed pipes 22 and 23 to the outer ends of the feed passages 26 and 27 through a passage in each classifier such as designated 28 in classifier 24 (Fig. 2) which is controlled by a damper or valve 29. The material is fed into the drum through both trunnions simultaneously by the feed screws 30 and 31 mounted respectively on tubes 32 and 33 which extend for the entire lengths of the feed passages. These tubes are supported at their inner ends by suitable supporting means 34 secured to the drum which also serve to rotate the tubes and the feed screws. The tubes are supported at their outer ends in bearings in the classifiers.

Air under pressure, preferably preheated, is supplied from a suitable source through air conduits 35 and 36 disposed at the sides of the combined feeders and classifiers 24 and 25 to the tubes 32 and 33 through a plurality of longitudinal slots 37 in the outer ends of the tubes. Dampers 35' and 36' control the air conduits 35 and 36 respectively. In this manner preheated air is supplied simultaneously at both ends to the drum after the pressure of the air has been converted into a relatively high velocity with the result that the drum operates under a suction and not under pressure. The air supplied at both ends to the drum flows over the ball and material charge therein to approximately the center of the mill and in doing so picks up material which has been pulverized. The air streams impinge upon each other at the center of the drum where their directions of flow are reversed, and the material and air mixture flows out of the drum simultaneously at both ends thereof through the passages 26 and 27 over the feed screws 30 and 31. The outer end portions of the passages 26 and 27 are connected to the lower ends of the classifiers 24 and 25 respectively. The material and air mixture flows from each of these passages into a vertically inclined passage in each classifier such as passage 38 in classifier 24, which connects with a curved passage in each classifier such as passage 39, generally of inverted U form, by means of which passages the mixture is delivered to the delivery pipes 40 and 41 respectively. These pipes are vertically inclined and are connected at their upper ends to a union 42 through which the pulverized material and air mixture is delivered to a conduit 43 which conducts the mixture to an exhauster fan 44 by which it is impelled through a conduit 45 to burners or to storage. The exhauster fan in this instance is driven by an electric motor 46. The conduit 43 is provided with an opening to the atmosphere which is controlled so that air may be drawn into the conduit 43 from the atmosphere in the desired volume to thereby control the capacity output of the mill. This means may take the form of a damper pivoted at one end which may be manually adjusted by an arm 47. Automatic means may be provided to release the damper so that it will move to a position in which the opening to the atmosphere in the conduit is fully open and the

conduit 43 is completely closed upon the occurrence of any accident to the mill or its associated equipment which might cause a cessation or retardation of the flow from the mill of the pulverized material and air mixture thereby avoiding flame propagation from a furnace to the mill and consequent explosion or other damage.

It will be understood that the classifiers may be of any desired form and that the type of classifier shown is to be considered as a preferred form only. The degree of separation of material from the pulverized material and air mixture or the fineness of the mixture leaving the classifier may be controlled by dampers suitably positioned in the classifier, such as the dampers 48, 49 and 50. It will be understood that as the pulverized material and air mixture flows downwardly through the outlet end of the curved passage 39 into the conduits 40 and 41, the oversize material will be deposited in the hopper 51 and will be returned to the feed passages 26 and 27 by means of a valve 52 in each classifier, which in this instance is operatively connected to the feed screws 30 and 31 by suitable driving mechanism 53 which serves to rotate the valves about their axes. In this manner, the oversize material is returned to both ends of the mill simultaneously along with the original feed.

With this arrangement it will be perceived that the outlet flow area from the mill for the relatively dense pulverized material and air mixture is greatly increased over prior arrangements and in some instances is approximately doubled. Although the flow area available through the tubes supporting the feed screws is somewhat smaller than in prior arrangements generally, the available pressure of the air is converted into a relatively high velocity in these small tubes thereby utilizing the pressure rather than wasting it by throttling as has heretofore been done, with the result that the air pressure is fully utilized without putting the mill under superatmospheric pressure. By simultaneously feeding the material to be pulverized at both ends of the drum, the effectiveness of the ball charge is increased for the reason that the time required for the feed to be absorbed within the ball charge is materially reduced as compared with prior practice. This is due to the fact that the material will travel from both ends or from oppositely disposed points toward the middle of the drum where the tendency of the material to ball ratio to increase will cause most of the material to go into suspension in the stream of air flowing through the drum.

With prior types of pulverizing mills, there is a tendency toward unstable operation when the air flow through the mill is increased above normal in an effort to increase the output of the mill which is due to the fact that the level of the material in the mill has a tendency to build up at the outlet end thereof. As the velocity of the air is increased, the resistance increases and as the level of the material increases the resistance further increases so that there results a self-accelerating condition which at times leads to the plugging of the mill. By feeding the material to be pulverized at both ends, or at different or oppositely disposed portions thereof, and with classifiers disposed at both outlets of the mill as in the form of the invention illustrated, the resistance to the outflow of the pulverized material and air mixture will be very materially reduced and the level of the material and oversize within the classifiers will also be materially re-

duced. Moreover, with air blowing through each classifier into the mill there will be a tendency to prevent the material level from building up at the outlets of the mill for the reason that the tendency in the present arrangement is for the material to build up near the center of the ball charge at the center of the mill. As a result, with the present arrangement it is possible to force the mill to higher capacities than has heretofore been attained before an unstable operating condition is reached.

The output with the present arrangement will normally be from 50 to 100 percent greater than with prior arrangements due to the greater effectiveness of the ball charge and also due to the fact that it is possible to greatly reduce the fineness of the material and hence the work done thereon.

Instead of the particular form of mill shown in Figs. 1 to 3, other forms may be utilized. For example, the mill may be formed as indicated in Fig. 4, with the walls 60 thereof converging from the central portion toward each end, or the mill or drum may be made cylindrical in form and liners may be used to provide the same effect, that is, with a larger grinding area at the middle of the drum than at both ends. These forms of mill tend to pull the charge away from the outlets at both ends and also tend to move the coarse material toward the center of the mill thereby increasing the time of contact of the material with the grinding elements which will result in increased efficiency of pulverization.

If desired, the material to be pulverized may be fed into the mill at one end only, rather than at both ends simultaneously as previously described. This may be accomplished by closing one of the feed pipes 22 or 23, or by directing the material discharged from the feeder 20 in such manner that it enters only one of the feed pipes 22 or 23, or by closing the passage 28 in one of the classifiers by the damper or valve 29, or by any other suitable means. Otherwise the operation will be substantially the same as hereinbefore described, that is, air, preferably preheated, will be supplied to the drum simultaneously at both ends thereof, the pulverized material and air mixture will be withdrawn from the drum simultaneously at both ends thereof, and oversize material which is separated from the fuel and air mixture in the classifiers will be returned to the drum at both ends thereof simultaneously.

Since the arrangements herein disclosed may be varied in their several parts or in their entirety, and the methods may be altered in one or more of their constituent steps without departing from the principles of the invention, it will be understood that the invention is not to be limited except by the scope of the appended claims.

What is claimed is:

1. Pulverizing apparatus comprising a rotatable drum, pulverizing means in the drum, means for separately feeding material to be pulverized and air to the drum at substantially oppositely disposed points thereof through separate passages, and means for withdrawing pulverized material entrained in air from the drum at said substantially oppositely disposed points thereof through the passages through which material is fed to the drum.

2. Pulverizing apparatus comprising a drum, pulverizing means in the drum, groups of sep-

10 arate, axially disposed passages connecting with substantially oppositely disposed portions of the drum, means for feeding material to be pulverized to the drum through one passage of each group, means for supplying air through another passage of each group, means for withdrawing pulverized material from the drum through one of the passages of each group, means for separating oversize material from the pulverized material, and means for returning the oversize material to the drum through one of the passages of each group.

3. Pulverizing apparatus comprising a drum, pulverizing means in the drum, groups of separate, axially disposed passages connecting with substantially oppositely disposed portions of the drum, means for feeding material to be pulverized to the drum through an outer passage of each group, means for supplying air through an inner passage of each group, and means for withdrawing pulverized material from the drum through an outer passage of each group.

25 4. Pulverizing apparatus comprising a drum, pulverizing means in the drum, groups of two separate, axially disposed passages connecting with substantially oppositely disposed portions of the drum, means for feeding material to be pulverized to the drum through the outer passage of each group, means for supplying air through the inner passage of each group, and means for withdrawing pulverized material from the drum through the outer passage of each group.

30 5. Pulverizing apparatus comprising a drum, pulverizing means in the drum, groups of separate, axially disposed passages connecting with substantially oppositely disposed portions of the drum, means for feeding material to be pulverized to the drum through one passage of one group, means for supplying air through another passage of each group, and means for withdrawing pulverized material from the drum through one of the passages of each group.

35 6. Pulverizing apparatus comprising a drum, pulverizing means in the drum, groups of separate, axially disposed passages connecting with substantially oppositely disposed portions of the drum, means for feeding material to be pulverized to the drum through one passage of one group, means for supplying air through another passage of each group, means for withdrawing pulverized material from the drum through one of the passages of each group, means for separating oversize material from the pulverized material, and means for returning the oversize material to the drum through one of the passages of each group.

40 7. Pulverizing apparatus comprising a drum, pulverizing means in the drum, means providing substantially co-axially arranged passages connecting with the drum, means for supplying air to the inner passage for delivery therethrough to the drum, means for supplying material to be pulverized to an outer passage, and rotatable helical means in said outer passage for moving the material supplied thereto into the drum, said helical means being disposed in the outer peripheral portion of said outer passage to provide a flow path in the inner peripheral portion thereof through which pulverized material entrained in air may be withdrawn from the drum.

45 8. Pulverizing apparatus comprising a drum, pulverizing means in the drum, means forming a passage connecting with the interior of the drum, a tubular member in said passage spaced

from the inner wall thereof, means for supplying air to the tubular member for flow therethrough to the drum, means for supplying material to be pulverized to said passage, a helix in said passage for moving the material supplied thereto into the drum, and means for rotating the helix, the helix being disposed in the outer peripheral portion of said passage to provide a flow path in the inner peripheral portion thereof through which pulverized material entrained in air may be withdrawn from the drum.

9. Pulverizing apparatus comprising a drum rotatable about a substantially horizontal axis, pulverizing means in the drum, means forming a substantially horizontally disposed passage connecting with the interior of the drum, a tubular member in said passage spaced from the inner wall thereof, means for supplying air to the tubular member for flow therethrough to the drum, means for supplying material to be pulverized to said passage, a helix in said passage for moving the material supplied thereto into the drum,

means for connecting the tubular member to the drum to cause said member to be rotated with the drum, and means for connecting the helix to the tubular member to cause the helix to be rotated and to move the material in said passage into the drum, the helix being disposed in the outer peripheral portion of said passage to provide a flow path in the inner peripheral portion thereof through which pulverized material entrained in air may be withdrawn from the drum.

10. The method of pulverizing material which comprises feeding material to a pulverizing zone simultaneously at different portions thereof, supplying air to said zone simultaneously at said different portions thereof, withdrawing pulverized material from said zone simultaneously at said different portions, separating oversize material from the withdrawn pulverized material and returning the oversize material to said zone.

MARTIN FRISCH.
